UNITED STATES PATENT OFFICE.

JOSEPH H. BARKER, OF CINCINNATI, OHIO.

ADJUSTABLE TRACE-HOLDER.

SPECIFICATION forming part of Letters Patent No. 239,421, dated March 29, 1881.

Application filed November 22, 1880. (No model.)

To all whom it may concern:

Be it known that I, JOSEPH H. BARKER, a citizen of the United States, residing at Cincinnati, Ohio, have invented new and useful Improvements in Adjustable Trace-Holders, of which the following is a specification.

My invention relates to adjustable trace-holders used with plow-harness and in similar connections; and its object is to produce an economical article and one more convenient of use in adjusting the back-band connections, as required.

This invention consists in a novel construction of the frame of the trace-holder, and the improvements will be fully hereinafter described, and specifically pointed out in the claim.

My invention is embodied in mechanism illustrated in the accompanying drawings, in which—

Figure 1 is a plan view of my invention complete. Fig. 2 is a vertical section, and Fig. 3 a cross-section, of the same.

Similar letters of reference indicate similar parts in the drawings and specification.

In the drawings, A designates the frame, which is somewhat rectangular in form, open in the center, and of sufficient width to take in the back-band C. The upper cross-bar, a, of the frame extends straight across; but the lower bar, a², is bowed downward to give a support for the hook h in such manner as to preserve a clear opening in the frame about the hook for the convenient attachment of a ring (usually of considerable size) by which the trace-chain or supporting-link is held upon the hook h. About midway of the frame A is a cross-bar, a', which in use serves as one of the clamping-surfaces for the band.

The clamp itself consists of a narrow plate, B, which may be serrated on one edge for more securely holding the web of the band. The plate is extended into pivots b b at opposite ends, which engage in side supports, d, upon the frame, and is provided with tongues B' B', near opposite ends, projecting at right angles, or nearly so, for convenience of manipulation.

It will be observed from the construction and arrangement of parts that the edge of the plate B has a cam-movement in relation to the cross-bar a', such as to compress and hold the band C when the parts are in position, as shown in Fig. 2; and that the band may be

disengaged very conveniently by simply raising the tongues B', which moves back the clamp B; but when closed the pull of the band tightens the clamp and holds it secure, the tongues B' serving as stops to its movement.

It will also be observed from the position of the parts that the web of the band is not likely to be torn or cut by the serrated edge, as the serrations do not act as hooks or teeth engaging only the surface-threads of the web, as in construction formerly used, but clamp and compress the entire body of the material; and, further, that the movable clamping-plate enables the adjustment to be far more expeditiously and accurately effected than where the band is simply drawn over and upon hooks or teeth upon a fixed bar in relation to which the band has to be drawn back again to sink the teeth into the web.

The upper cross-bar, a, of the frame may be entirely dispensed with, as its only office is to aid slightly in holding the entire device flat upon the web, where it naturally remains without such aid.

It is obvious, also, that the serrations in the edge of the plate B may be omitted and a straight edge employed.

In the manufacture of the device I cast the frame A, with its cross-bars a and side lugs, d, in one piece, and the plate B, with its pivots b and tongues B', in another, both preferably of malleable iron, which are then connected and are ready for use without further manipulation.

Having described my invention, I claim and desire to secure by Letters Patent—

A trace-holder consisting of the open frame A, provided with the side supports, d, the cross-bar a', and the downwardly-bowed bar a², provided with the central curved hook, h, projecting in a curved path into the open portion of the frame in rear of the cross-bar a', in combination with a pivoted clamping-plate, B, having tongues B', the whole being constructed substantially as and for the purposes described.

In testimony whereof I have hereunto set my hand in the presence of two subscribing witnesses.

JOS. H. BARKER.
